THEODORE T. SEAL, OF WHEELING, WEST VIRGINIA, ASSIGNOR OF ONE-HALF TO W. O. HOUSTON, OF BELLAIRE, OHIO.

COMBINED THREAD HOLDER AND CUTTER.

1,377,284.

Specification of Letters Patent. Patented May 10, 1921.

Application filed February 14, 1920. Serial No. 358,701.

To all whom it may concern:

Be it known that I, THEODORE T. SEAL, a citizen of the United States of America, and resident of Wheeling, county of Ohio and 5 State of West Virginia, have invented certain new and useful Improvements in Combined Thread Holders and Cutters, of which the following is a specification.

This invention relates to thread-holding devices or attachments for sewing machines, and it has for its primary object to provide a simple, inexpensive and efficient clamp or holder by means of which the severed or loose ends of both the lower, or shuttle thread 15 and the upper, or needle, thread are securely retained following a stitching operation until the next subsequent stitching operation has commenced, thus not only preventing the needle-thread from being withdrawn from 20 the eye of the needle by a rapid upward movement of the take-up arm of the sewing machine when operation of the latter is started, but also insuring that concatenation will occur between said needle-thread and 25 the shuttle-thread from the very beginning of the next sewing operation.

A further result which flows from the retention of the needle-thread is that the free end of the latter is prevented from being 30 carried downward into the shuttle race where it will produce a "choke", as sometimes happens.

Another object of the invention is to provide a clamp or holder of the character mentioned which may be accurately adjusted to apply any desired tension for gripping the threads, or to suit any weight, or thickness, 35 of thread.

A still further object is to provide a device of the character referred to having associated therewith a cutting blade by means 40 of which the threads may be severed at the end of a sewing operation.

With these and other objects in view, the 45 invention resides in the features of construction which will hereinafter be described, reference being had to the accompanying drawings, in which—

Figure 1 is an end elevation of the head of 50 an ordinary type of sewing machine, showing my invention applied thereto, and—

Fig. 2 is a section on line 2—2, Fig. 1.

Referring to said drawings, 1 indicates the 55 head of the work-arm of a sewing machine which may be of any ordinary commercial

type, said head having a reciprocating needle-bar 2 carrying a needle 3, a presser-foot 4 and a carrying-bar 5 for said presser-foot. Secured to the presser-foot bar 5 by means of a screw 6 is the device which constitutes 60 the present invention, the same consisting of a single length or strip of thin resilient material, as sheet steel, which is doubled upon itself to form an elongated plate-like member 7 and a relatively overlying member 8. 65 Said member 7 is flat and plain throughout and is adapted to have its back seat closely in fixed position against a face of the presser-foot bar at a suitable point with its free end projecting laterally a suitable distance from 70 said bar. The member 8 has its middle portion or that portion which is penetrated by the screw 6, slightly bowed outward or away from the fixed member 7 so that tension may be exerted through adjustment of said screw 75 to regulate the width of the thread-receiving space between the fixed member 7 and the yieldable member 8 at the inner end of the entrance throat 9 which is formed by curving or inclining the free end 8^a of said yieldable member away from the fixed member. 80

Carried by one of the members of the clamp, preferably formed integral with the member 8 at the upper edge of the latter, is a narrow tongue 10 which is bent over into 85 overlying relation to the upper edge of the fixed member 7, crossing the intervening thread-receiving space at a point located just rearward of that at which the threads are to be gripped for retaining them in place. The 90 forward edge of said tongue 10 is beveled to an edge whereby is provided a cutting blade adapted for severing the needle and shuttle threads, designated 11 and 12 respectively, at the instant that the latter, drawn through 95 the throat 9, reach the point at which they will be firmly held by the pressure of the yieldable member 8 against the fixed member 7, which point is located at or adjacent to the forward end of the bow provided, as 100 aforesaid, in said yieldable member.

In practice, following the completion of a stitching operation and the raising of the presser-foot 4 and bar 5 to elevated position, the work is drawn outward slightly to afford 105 the necessary slack, whereupon both threads are drawn into the thread-receiving space and up against the blade 10 until severance is effected. The severed ends of said threads will be held or gripped at this point with 110

such slight pressure as is required to prevent trouble until following the first few reciprocations of the needle which occur when proceeding with the work.

5 It will be apparent that, due to the formation of the clamp of a single piece of metal, the device is self-contained and is rendered readily applicable to any and all types or makes of sewing machine. Further, doubled 10 upon itself as shown, it possesses a resilience which enable it to perform its function of retaining the thread ends in an efficient manner.

15 The facility with which adjustment of the members may be effected is augmented by the provision of the bow in the yieldable member 8 between the rear end of said member and the point at which it coöperates with the member 7 for gripping the 20 threads.

What is claimed is—

25 1. A thread-holding clamp for sewing machines, comprising, in combination with a support, a thin strip of resilient material doubled upon itself to form a pair of elongated members relatively disposed to provide an intermediate thread-receiving space, said members having registering holes therein intermediate their ends, and an attaching screw directed through said holes into the face of said support, the innermost of said members being held seated in fixed 30 relation to said support, and the outermost of said members being yieldable and adapted through adjustment of said screw to move relative to said innermost member for varying the capacity of said thread-receiving 35 space.

40 2. A thread-holding clamp for sewing machines, comprising, in combination with a support, a thin strip of resilient material doubled upon itself to form a pair of elongated members relatively disposed to provide an intermediate thread-receiving space, said members having registering holes therein intermediate their ends, and an attaching screw directed through said holes into the face of said support, the innermost of said members being held seated in fixed 45 relation to said support, and the outermost of said members being bent intermediate its ends into outwardly bowed form, said screw being projected through the bowed portion of said outer member and being adapted for 50 adjustment to regulate the clamping pressure exerted by the latter at the thread-holding 55 point.

3. A thread-holding clamp for sewing machines, comprising, in combination with a support, a thin strip of resilient material doubled upon itself to form a pair of elongated members relatively disposed to provide an intermediate thread-receiving space, one of said members having its free end inclined away from the other member to form a thread-entering throat, the outermost of said members being outwardly bowed intermediate its ends, and adjustable means associated with the bowed portion of said outer member whereby the resilient clamping pressure of the latter with respect to the inner member is regulated.

4. A thread-holding clamp for sewing machines, comprising, in combination with a support, a thin strip of resilient material doubled upon itself to form a pair of elongated members relatively disposed to provide an intermediate thread-receiving space, one of said members having its free end inclined away from the other member to form a thread-entering throat, the outermost of said members being outwardly bowed intermediate its ends, and an adjustable screw directed through the bowed portion of said outer member whereby the resilient clamping pressure of the latter with respect to the inner member is regulated.

5. A thread-holding clamp for sewing machines, comprising, in combination with a support, a thin strip of resilient material doubled upon itself to form a pair of elongated members relatively disposed to provide an intermediate thread-receiving space, one of said members having its free end inclined away from the other member to form a thread-entering throat, the outermost of said members being outwardly bowed intermediate its ends, a cutting blade carried by the upper edge of one of said members adjacent to the forward end of the bowed portion of the outer member, said blade being disposed transversely of said thread-receiving space, and an attaching screw penetrating said members and adapted for adjustment to regulate the clamping pressure of the outer member, said screw being directed through the bowed portion of the last mentioned member.

In testimony whereof I affix my signature in presence of two subscribing witnesses.

THEODORE T. SEAL.
